PAINT RESTORING OR MIXING DEVICE

Joseph Taccogna, New York, N. Y.

Application May 14, 1934, Serial No. 725,591

1 Claim. (Cl. 259—91)

The present invention relates to paint restoring or mixing devices, adapted for use in shaking cans of paints which have stood on shelves in storage or the like for a long time, and wherein the pigment of the paint has settled and separated from the oils and other fluid contents of the cans into one portion of the can and has solidified to more or less extent.

An object of the present invention is to provide a compact and economical machine which may be operated by hand or otherwise for supporting one or more cans of paint and when operated will shake the cans of paint back and forth in a bodily movement to insure the shifting of the contents of the cans and consequently the thorough mixing of the paint so as to restore it to normal condition.

Various attempts have been made heretofore to provide machines or devices of this general character but in such instances the vibration of the can has not been sufficient and usually operates by turning or moving the can about an axis within the body of the can so that the contents of the can is not bodily shifted between the ends or sides thereof and consequently a thorough mixing operation is not accomplished. With this in view the present invention provides a machine which moves the can back and forth in a desired path substantially lengthwise of the longitudinal axis of the can and moves the can through a sufficient distance to insure the complete bodily movement of the can and the setting up of the desired inertia of the contents of the can to insure its shifting as the can changes or reverses its direction of movement.

Another object of the invention is to provide a machine which may support cans of different sizes merely by the interchange of a small part thereof so that the machine may be adaptable to cans of different sizes and configurations.

With the foregoing and other objects in view, the invention will be more fully described hereinafter, and will be more particularly pointed out in the claim appended hereto.

In the drawings, wherein like symbols refer to like or corresponding parts throughout the several views,

Figure 1 is a top plan view of a construction of paint can shaker embodying the features of the present invention.

Figure 2 is a front elevation of the same, showing the operation means therefor.

Figure 3 is a vertical section taken on the line 3—3 through Figure 1.

Figure 4 is a top plan view of a modified con-

struction of shaker wherein the cans are reciprocated back and forth in an arcuate path.

Figure 5 is a fragmentary end elevation of the same.

Figure 6 is a side view of a modified form of my invention.

Figure 7 is a vertical section taken on line 7—7 of Figure 8.

Figure 8 is a vertical section taken on line 8—8 of Figure 6.

Figure 9 is a diagrammatic view showing the movement of the can when being operated upon.

Figure 10 is a diagram showing the movement of the contents of the can; and

Figure 11 is a transverse section of a modified form of can support, adapted to various sizes of cans.

Referring now to the drawings, and first to the form shown in Figures 1, 2, and 3, 10 designates a frame or body portion which may be of any suitable configuration and size to support the mechanism and the cans of paint, and which is shown in the present instance as having an intermediate gear case or enclosure through which is mounted a vertical shaft 11 provided with a step bearing 12 at its lower end and which extends upwardly through the casing into the upper part of the frame. The shaft 11 is provided near its lower end with a beveled gear 13 which meshes with a second correspondingly beveled gear 14 fixed upon a horizontal shaft 15 which is suitably mounted in the side of the frame and has on its outer end a crank handle 16 by means of which the shaft 15 may be turned by hand, and which may also be provided with a pulley 17 by means of which the shaft may be driven by a motor or the like.

Detachably fixed upon the upper end of the shaft 11 is a disc 18 having a hub embracing the shaft 11 and carrying a set screw 19 or the like 40 by means of which the disc is fixed in desired position upon the shaft 11. The disc 18 carries an upstanding pin 20 which is mounted eccentrically on the disc 18 and to which is hinged one end of a link 21 for swinging and reciprocating 45 the link.

The frame or body portion is provided at its corners, or otherwise suitably spaced apart with ports 22 across which are mounted guide rods 23, there being a pair of the guide rods and the same 50 being disposed in parallel spaced apart relation to form a guide upon which a carrier 24 is mounted. The carrier 24 is provided with blocks or bars 25 across its under side at spaced points 55 suitably apertured to engage the guide rods 23 55

for holding the carriage thereto and guide the carriage for back and forth reciprocating movement. The other end of the link 21 is pivotally connected by a screw 26 or the like to the under side of the carrier 24, preferably by engaging upwardly into one of the bars 25, and the body portion of the carrier 24 comprises a flat plate or strip interconnecting the bars 25.

A tray or holder 27 is mounted upon the upper side of the carriage 24 by means of a removable screw 28 so that the tray or holder may be interchanged according to the size and configuration of the paint cans to be mounted in the device. In the present instance, as shown particularly in Figure 1, the tray 27 is provided with two compartments divided by a central partition 29 and is adapted to hold two cans of paint, the longitudinal axes of the compartments extending in the same general direction as that of the 20 guide rods 23.

It will be noted from Figure 2 that the lower side portions of the holder or tray 27 may be curved inwardly to conform to the general configuration of round cans. The tray, of course, 25 may be given other dimensions and configurations, and the tray may be quickly and easily interchanged upon the carrier by manipulation of the one or more screws 28 used.

In the operation of this form of the invention 30 the shaft 15 is turned, either by the crank handle 16 or the pulley 17. The vertical shaft 11 is thus rotated and the disc 18 is turned with the shaft so as to effect the eccentric rotary movement of the pin 20. The pin 20 thus reciprocates and 35 rocks the link 21 and as the latter is pivoted to the carrier 24, the carrier is moved back and forth on the guide rods 23 with sufficient rapidity, depending upon the rotation of the shaft 11, to violently shake the cans of paint. As the cans 40 of paint are carried lengthwise of their axes back and forth on the carrier, the contents of the cans are thus bodily moved back and forth and consequently as the cans are changed in the direction of their movement the contents of the cans are 45 violently agitated and thoroughly mixed.

It will be noted that the parts are so proportioned as to the length of the link 21 and the relative positioning of the shaft 11 and the guides 23 that the reciprocating movements of the carrier between the ends of its stroke are continuous and uninterrupted and there is no dead center position as the pivot screw 26 is connected to the under side of the carrier 24 at one side of the medial plane of the carrier. The mechanism is 50 thus in position at all times for easy starting and less strain is imposed upon the working parts during the change in the direction of movement of the carrier.

In the modification shown in Figures 4 and 5, 55 the device comprises a frame 30 of suitable construction to support a vertical shaft 31 provided at its lower end portion with a beveled gear wheel 32 which meshes with a second beveled gear wheel 33 disposed on a shaft 34 mounted in the frame at right angles to the shaft 31. The shaft 34 has adjustably fixed thereto a reciprocating arm 35 which extends laterally from the shaft 34 and the gear wheel 33 and which is pivotally connected at its outer end to one end of a link 36 60 which extends upwardly and inwardly and is pivoted at its upper end to an eccentric pin 37 mounted on a disc 38. The disc 38 is carried by an operating shaft 39 which may be driven by a pulley 40 or the like for turning the shaft.

75 It will be noted that the pin 37 on the disc 38

is mounted on a short radius relative to its shaft 39 as compared with the long radius or length of the reciprocating arm 35 on the shaft 34. The result is that the disc with its pin 37 may be continuously rotated in one direction to actuate the link 36 and thus rock the long arm 35 back and forth and impart, through the gearing 33 and 32, a rotary reciprocating motion to the vertical shaft 31.

Detachably mounted on the upper end of the 10 shaft 31 is a hub 40 by means of a set screw 41 or the like and this hub is provided with a plurality of trays or holders 42 for cans of paint, the same being disposed in substantially a circular row about the hub and with the longitudinal 15 axes of the holders 42 in the general circumferential direction of the hub. The cans of paint are adapted to be mounted in the holders 42 and when the shaft 31 is turned first in one direction and then in an opposite direction, the cans of 20 paint are bodily swung about the axis of the shaft 31 so as to insure the bodily movement of the contents of the can and consequently the bodily shifting of the contents from end to end in the cans at each change in the direction of move- 25 ment of the cans.

This modified form of the invention imparts a rotary reciprocating bodily movement to the cans of paint, the amplitude of which is regulated by the length of the arm 35 and the relative position- 30 of the eccentric pin 37 on the disc 38.

Another modified form of my invention embodying the same mode of operation as heretofore described, is, namely, the shaking of the contents of the can from end to end, but adding to this move- 35 ment of the can another movement.

The case 50 has a bracket 51 having a bearing 52, in which a shaft 53 rotates. The shaft 53 has at its free end a pulley 54, for a belt drive, and a handle 55 for manual operation. Any power 40 mechanism as a motor may be applied to the shaft in place thereof. The other end of the shaft 53, has a disc 56, with an off center pin 57, and this pin 57 engages a piston rod 58 and has pivoted connection therewith. The piston rod 58 slides up- 45 wardly and downwardly in a pivoted bracket 59, having its free ends 60 engaging in the downwardly extending brackets 61, supported by the top wall of the casing 50. The piston rod 58 passes out of the casing through an opening 63 and 50 supports a can holder 64. By rotating the shaft 53, the can holder 64 is moved upwardly and downwardly and at the same time laterally from the position indicated in full lines in Fig. 9, and by the reference character 65, to the upward posi- 55 tion indicated in dotted lines and by the reference character 66, to the extreme other lateral position indicated in dotted lines and by reference character 67. By this continued movement the contents of the can are moved in the direction of the 60 arrow 69, as shown in Fig. 10.

To enable the device to shake different sized cans, a can holder 70 is provided, which has a circular or annular rim 72, with a set-screw 73 to fasten a small sized can.

A larger concentric rim 74 with a set-screw 75 can hold a larger sized can, and the largest concentric rim 76 with set-screw 77 can hold the largest sized can. As shown in dotted lines, each larger sized can then rests on the rim adapted to 70 the smaller sized can or cans. The can holder shown in Fig. 11 takes the place of the can holder 64 shown in Fig. 8.

By this modified form the contents of the can is subjected to a simultaneously end to end shak- 75

ing and at the same time to a side to side action, whereby all of the contents of the can are thoroughly intermixed.

This modified form has the special advantage 5 that it is inexpensive to install, and may be used in smaller paint stores, and can be operated while the customer is making his purchases, and thereby the customer is assured of taking with him a thoroughly mixed can of paint, ready for immediate use.

It is obvious that various changes and modifications may be made in the details of construction and design of the above specifically described embodiment of this invention without departing 10 from the spirit thereof, such changes and modifications being restricted only by the scope of the following claim:—

What is claimed is:—

A means for mixing the vehicle for paint with the pigment which has settled to the bottom of the can comprising a housing, upwardly extending supports secured to the housing, horizontal guide means secured to the supports in upwardly spaced relation to the housing, a vertically disposed shaft journalled in the housing and extending above the top of the housing, a carriage reciprocable on the guide means, said carriage including a can receiving tray, coating means carried by the carriage and the upper portion of the shaft to reciprocate the carriage on the guide means upon rotation of the shaft, and a drive shaft operatively connected to the first named shaft. 15
